(57) **CLAIM**

The ornamental design for keyboard with game controls, as shown and described.

DESCRIPTION

FIG. 1 is an upper perspective view of a keyboard with game controls showing our new design;

FIG. 2 is a lower perspective view thereof;

FIG. 3 is a top plan view thereof;

FIG. 4 is a rear elevational view thereof;

FIG. 5 is a left side elevational view, the right side elevational view being a mirror image thereof; and, FIG. 6 is a front elevational view thereof.

The broken lines are for illustrative purpose only and form no part of the claimed design.
